DESIGN FOR A SWIMMING SUIT

Margit Fellegi, Los Angeles, Calif., assignor to Cole of California, Inc., Los Angeles, Calif., a corporation of California

Application December 9, 1940, Serial No. 97,176

Term of patent 7 years

To all whom it may concern:

Be it known, that I, Margit Fellegi, a citizen of the United States and residing at Los Angeles, in the county of Los Angeles and State of California, have invented a new, original, and ornamental Design for a Swimming Suit, of which the following is a specification, reference being had to the accompanying drawing, forming part thereof,

In the drawing:

Fig. 1 is a front elevational view of a swimming suit showing my new design; and Fig. 2 is a back elevational view thereof.

I claim:

The ornamental design for a swimming suit,
as shown.

MARGIT FELLEGI.
